UNITED STATES PATENT OFFICE.

WALTER JAMES THOMAS MCLEAN, OF ELTHAM, VICTORIA, AUSTRALIA, ASSIGNOR TO
THE M. B. RAIL ANCHOR LIMITED, OF MELBOURNE, AUSTRALIA.

MECHANISM FOR METAL-WORKING MACHINES.

Application filed May 8, 1925, Serial No. 28,869, and in Australia October 6, 1924.

My invention relates to improvements in mechanism for metal-working machines for bending, punching, pressing, upsetting, cutting, or shearing, and may include in combination subsidiary means for rolling; and the objects of my improvements are, firstly, to provide mechanism such that a shorter and more powerful stroke than usual may be obtained with the same expenditure of power and, secondly, to provide mechanism of compact and relatively light construction by which the above specified operations may be performed.

I attain these objects by the mechanism illustrated in the accompanying drawing, in which—

Fig. 1 is a side elevation of the machine, part of the automatic clamping means being omitted for the sake of clearness;

Fig. 2 is a plan of the machine;

Fig. 3 is an end elevation of the same;

Fig. 4 is an enlarged view showing the contour of the face of a roller;

Fig. 5 is a section through 5—5 on Fig. 6 and shows the rack and associated parts;

Fig. 6 is a section through 6—6 on Fig. 5;

Fig. 7 is an enlarged view of the forked bracket nipping a chain;

Fig. 8 is an elevation of the same;

Fig. 9 is a sectional elevation through 9—9 on Fig. 5 showing the pawls in engagement with the rack;

Fig. 10 is a plan of a modification of the machine which is provided with a rack at each end;

Fig. 11 is an enlarged view showing a rack-faced crank-arm in engagement with the end of the main shaft;

Fig. 12 is a side elevation of the same showing also a connecting rod and tool-carrier.

A sliding tool-carrier in the form of a rack-block 1 carries the tool 2 or other actuated part and is progressively driven forward by a sliding drive-block 3 which is pivoted to the end of a connecting rod 4 driven by an eccentric 5 mounted on the main shaft 6. The forward end of the drive-block is provided with a pawl 7 which engages a tooth such as 9 on the rack 10 during the forward stroke of the connecting rod and slides rearwardly over the next adjacent tooth 11 during the reverse stroke of the connecting rod so that, for example, if the stroke of the connecting rod is 1 inch

and the distance between the adjacent teeth on the rack-block is also 1 inch, the rack-block will carry the tool forwardly 1 inch for each stroke of the connecting rod and will continue to carry it forward stroke by stroke until the pawl has reached the last tooth. The rack-block and tool may be withdrawn by raising the first pawl 7 out of operative position and lowering a second pawl 12 which engages reversely-directed teeth 13 on the rack-block so that each stroke of the connecting rod withdraws the rack 1 inch. This withdrawal movement may be used either for returning the mechanism to its starting position or for operative purposes. By this means a machine of relatively light construction may be adapted to exert a short powerful stroke which is built up progressively step-by-step so as to obtain an equally good or better result than a machine of much heavier construction. If a step-by-step movement is not desired in any particular operation, both pawls may be engaged and the rack-block will then be withdrawn during the rearward stroke of the connecting rod to the same extent as it is advanced during the forward stroke and the tool will then have a definite short stroke.

Normally the rack is provided with twelve (12) teeth and the stroke of the connecting rod is 1 inch, but obviously the number of teeth may be varied and the length of stroke and distance between the adjacent teeth may also be varied as desired. The machine is mounted on a suitable base such as on longitudinal girders 14 suitably braced and connected together by cross girders 14^A and the ends of the girders 14 are adapted to support the work-holder 15, being provided with bolt holes 16. The sides of the rack-blocks will be bevelled laterally at 17 and side guide-plates 18, which are correspondingly bevelled at 19, will be bolted to the girder frame. To adjust these guide-plates for wear they may be planed off on their lower surfaces 20 to the extent necessary, whenever desired, or liner plates may be provided between the guide plates and the girder frame and these liner plates may be removed when it is necessary to adjust the guide plates on account of wear.

On the other end of the machine a second connecting rod 21 and operative parts may be provided, the head 22 of this con-

necting rod being bifurcated so that it may be driven by lateral extensions 23 of the eccentric on the main shaft. The head of the first connecting rod is accommodated within the bifurcation of the second connecting rod. The smaller end of the second connecting rod is pivotally connected either to a second drive-block 3^A which co-operates with a second rack-block 1^A (Fig. 10), which with its associated parts is similar to the rack-block 1 and its associated parts, or preferably to a second drive-block 24 (Fig. 2) which is connected to a sliding tool-carrier 25 by means of a partly counter-balanced gravitationally operated wedge 26. This wedge slides downwardly between the second drive-block and the sliding tool-carrier during the return stroke of the second connecting rod so that the sliding tool-carrier is forced rearwardly step-by-step by the motion of the second connecting rod. The wedge is provided with lateral lugs 27 which are accommodated in vertical recesses 28 in the sliding drive-block and tool-carrier so that the raising of the wedge by a slight pressure on the counter weights 29 causes the sliding tool-carrier to be withdrawn progressively. The wedge is almost counter-balanced by means of counter weights and a chain 30 (Fig. 3) passing over pulleys 31. A limit stop 32 may be provided to limit the movement of the wedge. In addition the wedge can be held stationary in any position by nipping the chain in a forked bracket 32^A (Figs. 1, 3, 7 and 8). By each of these means a definite stroke may be obtained as desired. Very fine adjustment of the stroke may be obtained by the use of this wedge. A second work-holder 15^A may be bolted in position through bolt holes 16^A.

The main shaft may be extended laterally, preferably on the side away from the fly-wheel and driving pulleys, and may be provided with an eccentric 33 actuating a vertical connecting rod 34 operating a tool-holder or the like 34^A, more especially for smaller work. The main shaft may be further extended and provided with a roller 35 against which a lower roller 36 for rolling hot iron or for welding may be brought to bear by means of a spring returned pedal-lever 37 and linkwork 38. Obviously the rollers may be of any desired contour, one form 36^A of which is shown in Fig. 4. This lateral extension of the shaft may be slotted diametrically on its end, the inner face of this slot 39 being preferably formed as a rack 40 so that a rack-faced crank-arm 41 (Fig. 11) may be secured to it in predetermined position by a screw 41^A. To one end of this crank-arm is pivoted a connecting rod 42 adapted to operate a sliding tool-carrier 43 (Fig. 12) fitted at the side of the machine. By varying the position of the crank-arm in relation to the main shaft the stroke of this

latter connecting rod may be varied as desired.

By the provision of a third longitudinal girder (not shown), the front and rear operative slides could be duplicated as will be obvious.

Automatic clamping means, for holding the work in position during the operation of the tool, comprises a sliding wedge 44 which is attached to a connecting rod 45 which receives its motion from a cam 46 which is keyed to the shaft 6. Obviously a duplicate set of clamping means could be placed on the opposite side of the eccentrics 23. In operation, the sliding wedge 44 actuates the jaws of a work-holder 15. A spring 47 keeps the connecting rod 45 in contact with the cam 46.

I claim—

1. The combination in mechanism for metal-working machines, of a horizontally reciprocating drive-block, a shaft, driving means actuated by the shaft, a connecting rod linking the drive-block to the driving means, with a pawl on the forward end of the drive-block, a sliding tool-carrier, a rack on the tool-carrier engaging the pawl progressively tooth-by-tooth; a second pawl on the drive-block, a second rack laterally contiguous to the first rack on the tool-carrier, a reversely-directed set of teeth on the second rack engaging the second pawl progressively tooth-by-tooth when the second pawl is lowered; and work-holding means.

2. The combination in mechanism for metal-working machines, of a reciprocating drive-block, a shaft, an eccentric on the shaft, a connecting rod linking the eccentric to the drive-block with a pawl on the forward end of the driver-block, a sliding tool-carrier, a rack on the tool-carrier engaging the said pawl progressively tooth-by-tooth, a second pawl on the drive-block, a second rack on the tool-carrier, a reversely-directed set of teeth on the second rack engaging the second pawl progressively tooth-by-tooth when the second pawl is lowered, work-holding means; a reversely-directed second connecting rod, a bifurcated head on the second connecting rod, lateral extensions of the said eccentric driving the said bifurcated head, a second reciprocating drive-block pivoted to the said connecting rod, a second sliding tool-carrier, means connecting the second drive-block to the second tool-carrier, and a second work-holding means associated with said second tool-carrier.

3. The combination in mechanism for metal-working machines, of a reciprocating drive-block, a shaft, an eccentric on the shaft, a connecting rod linking the eccentric to the drive-block, with a pawl on the forward end of the drive-block, a sliding tool-carrier, a rack on the tool-carrier engaging

the pawl progressively tooth-by-tooth, a second pawl on the drive-block, a second rack on the tool-carrier, a reversely-directed set of teeth on the second rack engaging the second pawl progressively tooth-by-tooth when the second pawl is lowered, work-holding means; a reversely-directed second connecting rod, a bifurcated head on the second connecting rod, lateral extensions of the said eccentric driving the said bifurcated head, a reciprocating drive-block pivoted to the second connecting rod, a second sliding tool-carrier, a gravitationally-operated wedge sliding vertically between the second drive-block and its tool-carrier, lateral lugs on the wedge slidably engaging recesses on the said drive-block and tool-carrier; and work holding means.

4. The combination in mechanism for metal-working machines, of a shaft, driving

means on the shaft, a tool-carrier driven progressively step-by-step from the shaft, with an extension on the shaft, an additional eccentric on the said extension, a vertical connecting rod driven by the said additional eccentric, a sliding tool-carrier pivoted to the said vertical connecting rod, a roller mounted on the said extension, a second roller co-operating with the first roller, a rack faced slot on the end of the said extension, a rack-faced crank-arm engaging the said slot, a connecting rod pivoted to said crank-arm and a sliding tool-carrier pivoted to said connecting rod; a rotary cam, a sliding wedge operated by the rotary cam, and work-holding jaws actuated by the sliding wedge.

In testimony whereof I affix my signature.

WALTER JAMES THOMAS McLEAN.
